CLAIM

The ornamental design for an oral therapy tool, as shown and described.

DESCRIPTION

FIG. 1 is a bottom, front, right perspective view of a first embodiment of the oral therapy tool, showing our new design;

FIG. 2 is a top, rear, left perspective view of the oral therapy tool of FIG. 1;

FIG. 3 is a right side elevation view of the oral therapy tool of FIG. 1;

FIG. 4 is a bottom plan view of the oral therapy tool of FIG. 1;

FIG. 5 is a left side elevation view of the oral therapy tool of FIG. 1;

FIG. 6 is a top plan view of the oral therapy tool of FIG. 1;

FIG. 7 is a front elevation view of the oral therapy tool of FIG. 1;

FIG. 8 is a rear elevation view of the oral therapy tool of FIG. 1;

FIG. 9 is a bottom, front, right perspective view of a second embodiment of the oral therapy tool;

FIG. 10 is a top, rear, left perspective view of the oral therapy tool of FIG. 9;

FIG. 11 is a right side elevation view of the oral therapy tool of FIG. 9;

FIG. 12 is a bottom plan view of the oral therapy tool of FIG. 9;

FIG. 13 is a left side elevation view of the oral therapy tool of FIG. 9;

FIG. 14 is a top plan view of the oral therapy tool of FIG. 9;

FIG. 15 is a front elevation view of the oral therapy tool of FIG. 9; and,

FIG. 16 is a rear elevation view of the oral therapy tool of FIG. 9.

The broken lines in the drawings show portions of the oral therapy tool that form no part of the claimed design.
